INVALID BED ACCESSORY

John A. Johnson, Clinton, Iowa

Application July 3, 1937, Serial No. 151,798

6 Claims. (Cl. 5—62)

This invention relates to apparatus for use in connection with hospital beds and the like by which a bedridden patient may be moved into various positions most suited to his comfort and welfare.

While I am aware that apparatus has heretofore been employed for tilting the mattress or spring frame of the bed, or a portion thereof, so as to elevate the head or the feet of a patient, such mechanisms have either been hand operated by means of a crank, or, if motor operated, have involved cumbersome mechanisms which restricted the functions and rendered the operation unsatisfactory.

15 The primary purpose of my present invention is to provide an accessory which may be utilized as a whole to elevate the upper portion of the patient's body or simultaneously or independently thereof to elevate the knees, and also separately 20 to elevate one end of the mattress frame as a whole so as to place the patient in an inclined position while lying prone upon the mattress. Furthermore, my invention contemplates a partial utilization only of the entire mechanism so 25 that merely the back rest portion may be applied to an ordinary bed and may be automatically raised and lowered to position the upper portion of the patient's body at any desired inclination.

30 A further purpose of the invention is to provide an apparatus which can be manipulated and controlled by the patient himself, so that he may change his position at will without the assistance of an attendant, thereby contributing materially to the patient's comfort.

35 Another object is to provide an apparatus which will operate smoothly and without imparting vibrations, shocks, or jars to the bed or to the patient and one which can be economically manufactured and readily attached at relatively 40 small expense to a standard hospital bed.

Other objects and many of the attendant advantages of my invention will be readily appreciated as the same becomes better understood by reference to the following description when considered in connection with the accompanying drawings.

Referring to the drawings:

Fig. 1 is a side elevation of a hospital bed equipped with my invention;

50 Fig. 2 is a diagram of the electric circuits employed; and

Fig. 3 is a schematic view, partially in section, showing various details of the apparatus.

Referring to the drawings more in detail, reference character 5 indicates the head, 6 the foot,

and 7 the side rails of a standard hospital bed, including the mattress or spring frame 8 pivoted at 9 to the head and supported at its opposite end upon the brackets 11.

My invention contemplates an auxiliary or supplemental frame adapted to be attached to and to overlie the frame 8 and, as will be apparent from Fig. 1, comprises a section 12 secured by clamps 13, or otherwise, to the frame 8, a back rest section 14 pivoted to the section 12 at 15, 10 an upper leg section 16 pivoted to the fixed section 12 at 17 and a lower leg section 18 pivoted to the section 16 at 19. Normally all sections of the supplemental frame will lie flat upon the frame 8 and support the mattress 21 in horizontal position, as indicated in dotted lines in Fig. 1. A supporting frame 22 extending transversely of the bed is clamped or otherwise fixed to the side rails 7 and carries the mechanism for operating the back rest section. A pivoted yoke 20 or bail 23 suspended from the side members of the frame 22, as at 24, affords a support for a hydraulic cylinder 25 and a piston 26 is attached to a rod 27 extending through the top of the cylinder and pivotally connected at its upper end, 25 as indicated by 28, to the back rest section 14.

Fluid such as oil is supplied to the cylinder beneath the piston through a pipe 29 connected with a riser 31 which, through an elbow 32, is connected with the discharge side of a rotary 30 pressure pump 33. This pump is mounted in a closed chamber 34 which is partially filled with oil and is driven through the gearing 35, or other suitable driving connection, by an electric motor 36. The motor and the chamber are supported 35 upon a base 37 suspended by rods 38 from the frame 22.

A pipe 39 connected with the pump discharge opens into the upper part of the chamber and is provided with a shut-off valve 41, the stem 42 40 of which is provided with an arm 43 outside the chamber adapted to be operated by a flexible rod or wire 44 to open and close the valve. It will be apparent that when the pump is operated oil will be delivered from the chamber 34, with which 45 the intake side of the pump communicates through an intake port 45, through pipes 32, 31, and 29, to the cylinder 25, to thereby elevate the piston 26 and raise the back rest section 14 to any desired inclined position, one position being 50 shown in full lines in Fig. 1. When the motor is stopped the back rest will be retained in that position by a check valve 46 which precludes reverse flow of the oil from the cylinder. At such times the valve 41 is closed. When it is de- 55

sired to lower the back rest, the valve 41 is opened (in a manner to be later described) thereby permitting the oil to return from cylinder 25 through pipes 28, 31, and 39 into chamber 34, the rapidity of the lowering of the back rest being dependent, of course, upon the extent of opening of the valve 41.

Frame 47, somewhat similar to frame 22, extends across the side rails 1 near the foot of the bed and carries a yoke or bail 48 pivotally suspended at 49 from the frame and supporting a hydraulic cylinder 51, similar to cylinder 25, which is equipped with a piston 52 and a rod 53 projecting through the top of the cylinder. The frame section 16 is provided intermediate its ends with a cross-piece 54 having an abutment 55 adapted to be engaged by the upper end of the rod 53, whereby, when the rod is projected upwardly, the section 16 and the pivotally attached section 18 will be elevated into the position shown in full lines in Fig. 1, or to intermediate position, as desired, thereby elevating the knees of the patient.

The frame 8 is similarly equipped with a cross-piece 56 provided with an abutment 57 adapted to be engaged by the upper end of rod 53, so that instead of elevating the knee rest portion of the supplemental frame, the cylinder 51 may be utilized to elevate the foot end of the frame 8 as a whole about the head pivot 9 to thereby dispose the frame in an inclined position.

For purposes of swinging the cylinder upon its supporting bail 48 from a position beneath the abutment 19 to a position beneath the abutment 51, a rod 58 is connected at one end with the cylinder and at its other end with a lever 59 fulcrumed at 61 to a plate 62 at the side of the bed, a hand operating lever or handle 63 being fixedly associated with the lever 59 so that by swinging the lever 63 in a counter-clockwise direction (viewing Fig. 1) the cylinder 51 may be swung from operative position with respect to frame section 16 to operative position with respect to the frame 8. This change of position with consequent change in result can be readily effected by the patient, since the operating lever 63 is in convenient position at the side of the bed.

Piston 52 is hydraulically operated by oil or similar liquid in the same manner as piston 26, and for this purpose oil is supplied to cylinder 51 beneath piston 62 through a pipe 64 connected by a T including a two-way valve 65 with the pipe 31. This valve is connected through a link and lever 66 with a hand lever 67 which can be manipulated by the patient to direct the oil from the pump either to cylinder 25 or to cylinder 51 at will.

A hollow arm 68 pivoted to the head of the bed, so that it may be swung into convenient position for the patient or may be swung out of the way, carries a control box 69 provided with a fixed switch element 71 interposed in the electric lead lines 72 of the electric circuit which is connected with a source of power through an ordinary plug 73. A movable element 74 adapted to close the circuit across the terminals of 71 is mounted in the control box in position to be elevated into the dotted line position shown in Fig. 3 by a cam 75 fixed upon a shaft 76 which extends outside one face of the control box where it is equipped with an operating handle 77 in position accessible to the patient. Normally this lever will stand in the off position indicated in Fig. 3, but when elevating movement is desired the patient swings the lever to the up position

illustrated, thereby closing the motor circuit to cause the pump to supply oil under pressure to one or the other of the cylinders 25 or 51, as determined by the position of control lever 67, to elevate the back rest or the knee rest, as desired. 5

A lever 78 fixed on the shaft 76 is connected with the flexible wire or rod 44 extending through the arm 68 to operate the valve 41. When control lever 77 is in the up position indicated in Fig. 3 valve 41 will be closed. When the patient desires to lower the back or knee rest, control lever 77 is moved to down position, thereby opening valve 41 and permitting the escape of oil from an elevating cylinder back into the chamber 34. 10

In order to limit the upward movement of the elevating pistons and to stop the motor when the desired elevation has been reached, the motor circuit includes two lines 79 and 81 in which are interposed the switches 82 and 83, respectively. 15 These switches are mounted on the cylinders 51 and 25 and are adapted to be operated by abutment fingers carried by the piston rods. Rod 27, for instance, carries an angular bar or rod 84 provided with abutment fingers 85 and 86 adapted, respectively, to open and close switch 83 when the rod 27 is in its upper or lower positions. The extent of upward movement may be varied by adjusting the position of the abutment finger 86 on the rod 84. Similarly, switch 82 is controlled by abutment fingers 87 and 88 mounted on rod 89 carried by piston rod 53. 20

The two lines 79 and 81 are rendered alternately operative by a control cam 91 carried by the shaft 92 on which control lever 67 is mounted. This cam is interposed between switch members 83 and 84 adapted to alternately cooperate with a fixed terminal 95 connected with line 72. II, for instance, lever 67 is set to direct oil from the pump to cylinder 25 through valve 65, switch member 83 will contact terminal 95, while the circuit through line 79 will be broken by depression of switch member 84. Also, if control lever 67 be set to deliver oil to cylinder 51 through valve 65, the cam 91 in this position of lever 67 25 will open the line 81 and close the line 79. 30

The mode of operation of my invention is substantially as follows:

Assuming that the mattress is horizontal and that the patient desires to elevate the back rest 14, he moves lever 67 in position to shut off pipes 64 and permit delivery of oil through pipe 31 and 28 to cylinder 25. He then swings lever 77 to up position, closing valve 41 and closing the motor circuit, thereby causing the delivery of oil under pressure from the pump into cylinder 25 to elevate the back rest. If he desires to stop the elevation in an intermediate position, he may do so by simply swinging the control lever 77 to off position. If, however, he desires full elevation, he lets the motor run until it is stopped by switch 83 when the abutment finger 86 in its upward movement throws the switch into open position. 55

Should the patient now desire to elevate the knee rest also, he swings control lever 67 into position to direct oil through valve 65 and pipe 64 into cylinder 51 and adjusts lever 77 to start the pump. The extent of elevation of the knee rest may be determined by the operator or will 60 be automatically stopped by switch 82, as has been previously explained.

In order to lower one or both of the rests, the patient manipulates control lever 77 to open valve 41, thereby releasing the pressure in the 75

elevating cylinder determined by the position of control lever 67 and the rest returns to horizontal position by gravity.

Should the patient desire to elevate the foot 5 of the mattress as a whole, he manipulates lever 63 when all of the parts are in lowered position, thereby bringing rod 53 into cooperative relation with abutment 51, whereupon the motor is started to perform the lifting operation, as previously 10 explained.

Obviously the principles of my invention may be embodied in a bed structure as a permanent part thereof, or the appliance may be attached to a standard bed as exemplified in the drawings.

15 It should be noted also that for cheaper installations the knee rest sections and the operating mechanism therefor may be entirely eliminated, leaving the back rest section and its operating mechanism as a unitary accessory for attachment to any standard hospital bed.

20 It is believed that my invention and many of its inherent advantages will be understood without further description, but it should be appreciated that the structural details illustrated and 25 described may be varied within wide limits without departing from the essence of the invention as defined in the following claims.

I claim:

1. In an accessory for an invalid bed having 30 a bed frame, the combination of a pivotally mounted back rest adapted to be pivotally supported on the bed frame, a swinging arm adapted to be mounted to swing about a vertical axis on the bed frame, a control box carried by the outer 35 end of said arm and adapted to be swung horizontally above the bed into position accessible to an occupant of the bed, means including a motor, a pump, a pipe line leading from the pump and a hydraulically operable piston adapted to be 40 mounted on the bed frame and operatively connected with said pipe line for actuating said back rest, a valve for controlling the fluid flow in said pipe line, a motor control switch, and a control lever carried by said control box and arranged to 45 actuate said switch and said valve for controlling the actuations of said back rest.

2. In an accessory for an invalid bed, the combination of a mattress supporting frame comprising a plurality of pivotally connected sections, hydraulic means including a pump and a piston for elevating one of said sections about its pivot, an electric motor connected to operate said pump, a horizontally swinging arm adapted to be mounted on the bed and provided with a control box adapted to be swung to a position above the bed accessible to the bed occupant, a motor control switch in said box, a control valve for the hydraulic means, a control lever on the box, and connections from said lever to said switch and valve for operating the same to cause the raising and lowering at will of said one pivotally mounted section.

3. The combination with a hospital bed of a frame pivotally connected thereto at one end, 55 a supplemental frame comprising a plurality of

pivots connected sections, one of said sections being attached to said first mentioned frame, hydraulic elevating mechanism including a motor, a pump, a cylinder adjustably carried by said bed and a piston therein provided with a rod extending upwardly from the cylinder, abutments carried by said frame and by a section of said supplemental frame, and manually controlled means for selectively positioning said cylinder so as to dispose said rod in cooperative relation to the 10 abutment of said frame or the abutment of said section to thereby enable the elevation of said frame or said section of said supplemental frame at will upon actuation of said elevating mechanism.

4. The combination with a hospital bed of a frame pivotally connected thereto at one end, a supplemental frame comprising a plurality of pivotally connected sections, one of said sections being attached to said first mentioned frame, 15 elevating mechanism adjustably carried by said bed, abutments carried by said frame and by a section of said supplemental frame, and manually controlled means for selectively positioning said elevating mechanism in cooperative relation to the abutment of said frame or the abutment of 20 said section to thereby enable the elevation of said frame or said section of said supplemental frame at will upon actuation of said elevating mechanism.

5. In an accessory for a hospital bed having a bed frame pivotally connected thereto at one end and a supplemental frame comprising a plurality of pivotally connected sections, one of said sections being pivotally connected to said first frame, 25 and abutments carried by said frame and a section of said supplemental frame, the combination of hydraulic elevating mechanism including a motor, a pump, a cylinder adapted to be adjustably carried by said bed and a piston therein provided with a rod extending upwardly from said cylinder, and means for selectively positioning said cylinder so as to dispose said rod in cooperative relation to the abutment of said frame or the abutment of said section to thereby enable 30 the elevation of said frame or said section of said supplemental frame at will upon the actuation of said elevating mechanism.

6. In an accessory for a hospital bed having a bed frame pivotally connected thereto at one end and a supplemental frame comprising a plurality of pivotally connected sections, one of said sections being pivotally connected to said first frame, 35 and abutments carried by said frame and a section of said supplemental frame, the combination of elevating mechanism adapted to be adjustably carried by said bed, and means for selectively positioning said elevating mechanism in cooperative relation to the abutment of said frame or the abutment of said section to thereby enable the 40 elevation of said frame or said section of said supplemental frame at will upon actuation of said elevating mechanism.

JOHN A. JOHNSON.
